[57] CLAIM

The ornamental design for a gun and handcuff holster, as shown and described.

DESCRIPTION

FIG. 1 is a perspective view of a gun and handcuff holster, showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

The broken line showing of a belt, gun and handcuffs in FIG. 1 is for illustrative purposes only and forms no part of the claimed design.

FIG. 1

FIG. 3

FIG. 4

FIG. 5

FIG. 6

FIG. 7
